OMER HEWES, OF KANKAKEE, ILLINOIS.

Letters Patent No. 80,735, dated August 4, 1868.

IMPROVED CAR-COUPING.

The Schedule referred to in these Letters Patent and making part of the same.

TO ALL WHOM IT MAY CONCERN:

Be it known that I, OMER HEWES, of the city of Kankakee, in the county of Kankakee, and State of Illinois, have invented a new and useful mode of coupling cars, entitled "Omer Hewes's Self-Coupling Car-Bumper;" and I hereby declare that the following is a full, clear, and exact description of the construction and operation of the same, reference being had to the annexed drawings, making a part of this specification.

Figure 1 is a perspective view.

Figure 2, a horizontal section.

Figure 3, a perspective view of coupling.

Figure 4, a transverse section of coupling.

Same letters refer to like parts.

A A is a bumper-box or frame, bolted to the under side of a car; B is the bumper-head; C C are two bars forming the sides of the bumper, and being connected with the bumper-head B, and the tie-block K, constitutes the bumper proper; D is the coupling; E E, coupling-jaws; F F, steel springs; G is a cam for spreading the springs, and disconnecting the coupling; H is a horizontal shaft to work the cam G; I is a perpendicular shaft to work the cam G; J, a position the horizontal shaft H will take to disconnect the coupling.

Its construction consists of the two wrought-iron bars C C, bolted to the tie-block K, and also to the cast-iron bumper-head B. It is made to work freely in the casing or box A A, and is provided with stops and springs, after the usual manner of holding in position, and giving elasticity in drawing and resisting the shocks to which it is subjected. The opening in the bumper-head is made of sufficient size to insure the point of the coupling under all circumstances to enter it. The opening diminishes in size from the front face, so as to form a bevel-surface with it, as shown in fig. 2, at b', and serves to guide the coupling to the coupling-jaws E E. The coupling-jaws E E are made of wrought iron, fastened by a bolt, in a knuckle-joint, in the angle formed at the back side of the bumper-head and the iron bars C C. The bolt is fitted tight in the jaw, and made to work loosely in the upper and lower plate of the bumper-head, so as to admit of its turning freely to and from the coupling D. To these jaws are attached the steel springs F F, by a bolt passing through a slot in the springs, so as to admit of the jaws turning in their knuckle-joints. They are firmly screwed to the iron side C C of the bumper, and so constructed as their elasticity will tend to close the jaws. By this means the coupling D, on entering the bumper-head, presses apart the jaws until they fly back behind the projection in the pyramidal point of the coupling, and becomes firmly attached to the bumper. The coupling is disconnected by means of the cam G, which is under control from either side of the car, by the horizontal shaft H, and from the platform or top of the car by the shaft I. The coupling D is forged of wrought iron, to such shape substantially as represented in figs. 3 and 4. The two ends are shaped so as to form a pyramidal head, the offset at the back of which is formed to receive the coupling-jaws. From the ends towards the centre of the coupling, the iron is reduced in thickness, by gradually widening the same, so as to form the angles as will conform to the bevel-surface in the bumper-heads, by which means the bumper carrying the coupling, forces it into the one to be coupled, and also admits of lost motion or slack, the taking up of which enables a train to get under headway, when otherwise it would be unable to start at all.

The advantages to be derived over any invention or coupling now in use, is the rapidity in making up a train of cars, or disconnecting the same, without risk or danger to life or limb; also by the peculiar formation of the coupling and the bumper, the difficulty, where one car stands higher than another by means of one being loaded and the other light, is obviated; and also when a car using this bumper and coupling is run out on to another road, or in connection with other cars not supplied with them, the coupling has only to be taken out and the ordinary link and pin inserted.

It will be seen that the coupling-jaws E operate as levers, and that any strain or pull upon the coupling D, increases the force with which said jaws act upon the shoulders of the coupling, thereby preventing the latter from being uncoupled until the jaws are released by the cam.

I claim the lever-jaws E, pivoted in the angle between the bumper-head B and the side bars C, and attached at their inner ends to the slotted springs F, in combination with the cam G, whereby the coupling-pin D is released from the lever-jaws by the action of the cam upon the springs, as herein shown and described.

OMER HEWES. [L. S.]
